UNITED STATES PATENT OFFICE.

ARTHUR P. HAGAR, OF NEWARK, NEW JERSEY, ASSIGNEE TO THE SAFETY CAR HEATING & LIGHTING COMPANY, A CORPORATION OF NEW JERSEY.

SIGNAL APPARATUS.

Application filed February 21, 1924. Serial No. 694,323.

To all whom it may concern:

Be it known that I, ARTHUR P. HAGAR, a citizen of the United States, and a resident of the city of Newark, county of Essex, and 60 State of New Jersey, have invented an Improvement in Signal Apparatus, of which the following is a specification.

This invention relates to signal apparatus and with regard to more specific features 10 thereof to apparatus for traffic signals and the like.

One of the objects of the invention is to provide apparatus of the above nature practical and efficient and capable of meeting 15 the requirements of use in a highly satisfactory manner. Another object is to provide apparatus of the above nature automatic in action and adapted to operate at all times dependably. Another object is to 20 provide such apparatus simple in construction and in which the various parts are compactly disposed. Another object is to provide such apparatus adapted to operate with a high degree of economy. Other objects 25 will be in part obvious or in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawings in which 30 are shown various possible embodiments of the several features of this invention:

Figure 1 is a vertical sectional elevation of a signal apparatus adapted for use as a traffic signal, a part thereof being broken 40 away in order not to encumber the drawing.

Figure 2 is an elevation partly in section and in enlarged detail showing certain parts of the apparatus of Figure 1.

Figure 3 is a top plan view of Figure 2, certain parts being shown in section.

Figure 4 is a view similar to Figure 3 showing the parts in another position and,

Figure 5 is a section taken substantially 50 along the line 5—5 of Figure 4.

Similar reference characters refer to similar parts throughout the several views of the drawings.

Referring now to the drawings in detail, 55 with reference first to Figure 1 there is

shown a standard 10 of a suitable design for positioning at the intersection of streets or highways, for example. This standard 10 is hollow in the form of a casing and within its lower portion is adapted to accommodate 60 a fuel reservoir such as a gas tank 11. The upper portion of the standard is preferably of reduced diameter as indicated at 12 and supported upon the top thereof is an annular flanged member 13 substantially L-shaped in cross-section as shown. This member 13 supports a suitable casing 14 within which is positioned a source of light, the mechanism of which is also supported by the member 13, as will be more fully described 70 hereinafter.

The casing 14 is formed of sheet metal, for example and is preferably of a globular shape. A chimney 15 is provided to permit the escape of heat or products of combustion and this chimney preferably has an overhanging covering 16 for protection against rain and wind. The embodiment of the invention shown in the drawings is adapted to be positioned at the intersection of 80 two streets or highways. The casing 14 is therefore provided with two pairs of oppositely disposed openings for the emission of light rays, from the source of light within the casing, along the lines of direction of 85 the two streets or highways. These openings are provided with suitable lenses 17 preferably of plain uncolored glass. The source of light is therefore adapted to be visible through the lenses 17 from either direction along each of the streets. 90

The light indicated generally by the numeral 18 in Figure 1 preferably takes the form of a gas burner and is supplied with energy from the gas tank 11 in the bottom 95 of the standard 10. The gas is stored under pressure in the tank 11 and is drawn off through a pressure regulator 19 wherein its pressure is reduced to a predetermined desired value. This pressure regulator 19 will 100 not be described in detail herein, its construction being preferably that disclosed in the application of John Rumpf, Serial No. 620,623 filed February 24, 1923. The gas taken from the pressure regulator 19 is conducted through a pipe or tubing 20 to mechanisms which will presently be described and to the gas burner.

As shown in Figure 1, and more clearly 110 in Figures 2 and 3, there are positioned

about the burner 18 four upright translucent screens 21, 22, 23 and 24. These screens are preferably of glass and the pair opposite each other are colored alike and in a color distinctive from that of the other opposite pair which are also colored alike. For example, the screens 21 and 23 may be colored green and the screens 22 and 24 colored red. Light rays from the burner 18 in order to have exit through the lenses 17, must pass through these colored screens. Therefore, when the green colored screens 21 and 23 are positioned in line with a pair of lenses 17, a green light will be visible from each direction on the street along which these lenses 17 are directed, the green indicating that traffic is open along that street. At the same time the red colored screens 22 and 24 are in line with the other two lenses 17 and a red light is visible from either direction on the street along which these lenses 17 are directed, the red light indicating that traffic is closed along that street. By moving all of the colored screens 25 around the burner 90° the relative positions of the colored screens with respect to the light will be interchanged and the color of light rays visible from the respective streets will be interchanged.

Referring now particularly to Figure 2, the four colored screens 21, 22, 23 and 24 are mounted upon a suitable frame 25 which is supported upon the flanged upper end 26 of a sleeve bearing 27. This sleeve 27 is 30 rotatably mounted preferably through ball-bearings 28 and 29 upon a vertical stationary shaft 30. The shaft 30 is supported in a plate member 31 which rests upon the vertical flange of the annular supporting member 13 before described. The colored screens are therefore rotatable about the burner 18. As shown in Figure 4 the sleeve bearing 27 is provided with a pin 32 which limits the rotation of the sleeve bearing and 35 of the colored screens by engagement with two stops 33 and 34 positioned on the upper surface of the plate member 31. The sleeve 27 may therefore rotate about the shaft 30 between the two stops 33 and 34 and the latter are so positioned that when the pin 32 is against either one of the stops, the four colored screens are positioned in line with the respective lenses 17, and further so that a rotation of the sleeve between the 40 two stops moves the screens 90°. Thus a rotation of the sleeve 27 in either direction between the two stops 33 and 34 interchanges the colors of the light rays emitted from the lenses 17, opening the traffic on the street which was previously closed and closing the traffic on the street which was previously opened.

Secured to the rotatable sleeve 27 is an upright pin 35 about which is slotted the end 45 of a lever 36. This lever 36 is pivoted at 37

upon a supporting plate 38 secured to the plate member 31. A movement of the lever 36 about its pivot 37 will therefore rotate the sleeve 27. This lever 36 has an upwardly extending end 36^a between which and the 50 downwardly extending end 39^a of a lever 39 is interposed a telescoping housing 40 containing a spring 41. This housing 40 bears against the arms 36^a and 39^a with tapered ends 40^a and 40^b and by means of 55 this construction a substantially frictionless contact is had between the levers 36 and 39. The lever 39 is pivoted upon the plate 38 at 42, as shown in Figure 3, and its right-hand end 39^b is provided with an opening 60 through which passes a shaft 43. A rotation of the lever 39 about its pivot 42 through the telescope spring connection 40 tends to bring the two levers 36 and 39 in line, placing the spring 41 under compression. The instant that the center line of the lever 39 passes beyond the pivot 37 of the lever 36, this compression in the spring 41 is released and quickly rotates the lever 36 about its pivot 37. This movement of the lever 36 rotates the sleeve 27 between the two stops 33 and 34 and turns the colored screens through 90°.

The shaft 43 is preferably provided with two collars 44 and 45, having tapered portions making contact with the end 39^b of the lever 39 so that axial movements of the shaft 43 are imparted to the lever 39 to rotate the latter about its pivot 42. The shaft 43 is connected through clamping nuts 46 100 to a diaphragm 47, the action of which will presently be described.

Turning now to Figure 2, there is shown the pipe or tube 20 through which gas is led from the tank 11 and pressure regulator 19. Part of the gas from this pipe 20 passes upwardly through a pipe 48 and thence through a passage 49 shown in Figure 3 to a pilot burner 50. A needle valve 51 regulates the flow of this gas to the 110 pilot burner 50. The remainder of the gas from the pipe 20 passes through a pipe 52 to a needle valve 53. This valve 53 controls the flow of gas from the pipe 52 to a passage 54 formed in a boss 55 upon the 115 cover plate 56 of a casing 57. This casing 57 is supported upon the supporting plate 38, and with the cover plate 56 and diaphragm 47 opposite thereto, forms a chamber 58. The diaphragm 47 is therefore responsive to gas pressure within the chamber 58 and movements thereof in response to gas pressure are imparted to the lever 39.

A pipe 59 is adapted to be in communication with the chamber 58 through a passage 60 and a valve seat 61 or through a passage 62 and a valve seat 63. The passage 54 to which gas is admitted from the pipe 52 through the needle valve 53 is in communication through a passage 64 with 125

the pipe 59 through the passage 60, and with the chamber 58 through the valve seat 61.

The passages through the valve seats 61 and 63 are controlled by valves 65 and 66 respectively which are mounted upon a rocker arm 67 pivoted as at 68 upon a boss 69 of the cover plate 56, shown more clearly in Figure 5. Pivoted at 70 upon another boss 71 of the cover plate 56 is a substantially U-shaped lever 72, the two arms of which extend opposite the ends of the pivoted valve carrying member 67. Between these arms of the U-shaped member 72 and the respective ends of the member 67 are interposed spiral compression springs 73 and 74 which are adjustable through the screws 75 and nuts 76. Pivoted upon the U-shaped member 72 as at 77 is a member 78 connected through pins 79 to move in response to movements of the diaphragm shaft 43. This member 78 has a projecting part 78^a which is slotted to receive the bent end of a lug 80 mounted upon the cover plate 56. The connection between the shaft 43 and the member 78 is nearer the slotted part 78^a than the pivot 77. Therefore a movement of the shaft 43 first swings the member 78 about its pivot 77 until the end of the slot is engaged by the lug 80, and thereupon further movement of the shaft 43 swings the U-shaped member 72 about its pivot 70. A movement of the member 72 about its pivot until the springs 73 and 74 pass beyond center quickly snaps the member 67 about its pivot closing one of the valves and opening the other.

Considering now more particularly the operation of this apparatus, it will be assumed at starting that the mechanism is in the position shown in Figure 3. The pin 32 on the rotatable sleeve 27 is against the stop 33 and the colored screens 21, 22, 23 and 24 are positioned in line with the respective lenses 17. Gas at the required pressure is drawn from the pressure regulator 19 through the pipe 20 and a small amount thereof passes through the pipe 48 to the pilot burner 50. The remainder of the gas from the pipe 20 passes through the pipe 52 and its entrance therefrom to the passage 54 is regulated by the valve 53. The gas thereupon traversing the passage 64, its path is divided, part going to the pipe 59 through the passage 60 and the remainder entering the chamber 58 through the valve seat 61. Pressure begins to build up in the chamber 58 and the diaphragm 47 starts to move outwardly. The member 78 in response to the movement of the diaphragm swings about its pivot 77 until the play permitted by the slotted connection 78^a is taken up. Upon further movement of the diaphragm the member 72 swings in a counter-clockwise direction as viewed in Figure 3 storing up energy in the springs 73 and 74. At the in-

stant that these springs pass beyond center with respect to each other, the member 67 is quickly snapped about its pivot by the springs 73 and 74 closing the valve 65 and opening the valve 66. The entrance to the chamber 58 being now closed, the gas discharges from the chamber 58 through the valve seat 63 and passage 62 to the pipe 59. It will be seen that a continual supply of gas is had to the pipe 59, the passage 60 maintaining this supply while the valve 66 is closed. Through this pipe 59 the gas is led to the burner 18 as will be described.

The outward movement of the diaphragm 47, as above described, through the shaft 43 swings the lever 39 about its pivot 42. This movement of the lever 39 lessens the distance between the points 40^a and 40^b, compressing the spring 41. As soon as the lever 39, swinging about its axis in counter-clockwise direction, passes beyond the pivot 37 of the lever 36, the energy stored in the spring 41 quickly swings the lever 36 about its pivot 37. This movement of the lever 36, through the pin 35, quickly rotates the sleeve 27 until the pin 32 strikes the stop 34, thus rotating the colored screens through 90° and interchanging the colors of the light rays emitted along the two intersecting streets or highways.

Interposed between the lever 39 and a lug 81 on the casing 57 is a spring 82 which is adjustable through the threaded connection of its supporting shaft 83 with the lug 81 and a lock nut 84. As the lever 39 swings in counter-clockwise direction about its pivot 42 in response to outward movement of the diaphragm 47 the spring 82 is compressed.

The parts are now in the position shown in Figure 4. The valve 66 is open and gas discharges from the chamber 58 resulting in reduction of pressure therein. The spring 82 expands swinging the lever 39 in a clockwise direction and forcing the diaphragm 47 inwardly again as the gas pressure in the chamber 58 decreases. The spring 82 is stronger than the spring 41 and energy is again stored in the latter until the lever 39 in its clockwise movement passes beyond the pivot of the lever 36, whereupon this energy is expended to quickly snap the lever 36 about its pivot again. This movement of the lever 36 returns the color screens to their original positions. The inward movement of the diaphragm 47 takes up the play permitted by the connection 78^a and thereupon the member 72 is swung about its pivot closing the valve 66 and opening the valve 65 through the compression and release of the springs 73 and 74. The parts are now back to the position shown in Figure 3 and gas again entering the chamber 58, through the valve seat 61, the action is repeated.

Referring now to Figures 2 and 3, the

pipe 59 leads to a chamber 85 formed in a boss 86 which supports the burner 18 and which is a part of a cover plate 87 for a casing 88. A needle valve 89 controls the supply of gas from the chamber 85 to the interior of the casing 88 and the mechanism therein. From the interior of the casing 88 the gas is led to the burner 18. This casing 88, with the mechanism contained therein, comprises a device for intermittently cutting off the flow of gas to the burner 18 to give a flashing light. The details of this construction are not shown nor described herein since the construction employed is preferably substantially that shown in the application of John Rumpf, Serial No. 621,122, filed February 26, 1923. However, it is to be noted that the valve 89 controls the rate of flow of gas to the burner 18 from the pipe 59 and hence the rate of discharge of gas from the chamber 58. The flashing mechanism, comprising the casing 88 and supporting the burner 18 and pilot burner 50, is preferably mounted upon the shaft 30 which is also hollowed out to permit passage of the pipes 48 and 59. It will be seen that there is described above a signal apparatus adapted for use as a highway signal and providing an automatically operated traffic directing device. When placed at the intersection of two streets, this device displays a green light along one of the streets and a red light along the other, and the colors of these lights are automatically interchanged at predetermined intervals of time. The period of time during which one color of light is directed along one of the streets may be regulated by adjustment of the valve 53 controlling the rate of flow of gas entering the chamber 58, and the period of time during which the other color of light is directed along the same street may be regulated by adjustment of the valve 89 which controls the rate of discharge of gas from the chamber 58. These periods being thus independently adjustable may be varied to any desired ratio. For example, if the signal apparatus is placed at intersecting highways, the periods of time of indicating open traffic on the two highways may be adjusted in proportion to the amount and importance of the traffic on these highways. The apparatus is economically operated and thoroughly dependable at all times, attaining many practical and useful advantages.

As many possible embodiments may be made of the above invention and as many changes might be made in the embodiment above set forth, it is to be understood that all matter hereinbefore set forth is to be interpreted as illustrative and not in a limiting sense.

I claim as my invention:

65 1. In signal apparatus, in combination, a

gas light, means adapted to give light rays emitted therefrom a predetermined color, means adapted to give said light rays a second predetermined color, means actuated by the flow of gas to said light adapted to render said two coloring means effective alternately upon said light rays for predetermined periods of time, means for adjusting the length of said period of time during which said first coloring means is effective upon said light rays, and means for adjusting the length of said period of time during which said second coloring means is effective upon said light rays.

2. In signal apparatus, in combination, a gas light, means adapted to direct light rays therefrom in two predetermined directions, a coloring means, a second coloring means, and means actuated by the flow of gas to said light adapted simultaneously to render said first coloring means effective upon rays directed in one of said directions and said second coloring means effective upon rays directed in said other direction for a predetermined period of time, and adapted simultaneously to render said first coloring means effective upon rays directed in said last direction and said second coloring means effective upon rays directed in said first direction for a predetermined period of time.

3. In signal apparatus, in combination, a gas light, means about said light comprising a member adapted to permit passage of light rays of a predetermined color and a second member angularly disposed relative to said first member adapted to permit passage of light rays of a second predetermined color, and means actuated by the flow of gas to said light adapted to move said first means at predetermined intervals of time to interchange the position of said two members with respect to the path of predetermined rays from said light.

4. In signal apparatus, in combination, a gas light, means about said light comprising a member adapted to permit passage of light rays of a predetermined color and a second member adapted to permit passage of light rays of a second predetermined color, and means actuated by the flow of gas to said light adapted to move said first means intermittently to position the same about said light with said two members in predetermined position with respect to said light for a predetermined period of time and to position the same about said light with the position of said two members interchanged with respect to said light for a second predetermined period of time.

5. In signal apparatus, in combination, a gas light, a device rotatably mounted adjacent said gas light comprising a light screening member, and means actuated by the flow of gas to said light adapted inter-

- mittently to rotate said device alternately to position said member in the path of predetermined rays from said light for a predetermined period of time and to position said member out of the path of said predetermined rays for a predetermined period of time and means for independently adjusting the length of said two periods of time.
6. In signal apparatus, in combination, a standard adapted to be positioned at a highway intersection, a casing supported by said standard having a passage for light rays along each of said highways, a gas burner within said casing, a source of gas supply within said standard, means for leading said gas from said source to said burner, means within said casing adapted to distinctively color light rays from said burner directed along said respective highways, and means actuated by the flow of gas to said burner adapted at predetermined intervals of time to move said last means to interchange the colors of said light rays directed along said respective highways.
7. In signal apparatus, in combination, a gas burner, a movable color screen, means adapted to lead a supply of gas to said burner, means actuated by said flow of gas adapted to intermittently and substantially instantaneously move said screen into and out of the path of predetermined rays from said burner, and means for independently adjusting the lengths of time during which said screen remains respectively in and out of the path of said rays.
8. In signal apparatus, in combination, a gas burner, a pair of color screens of distinctive colors, means adapted to lead a supply of gas to said burner, means actuated by said flow of gas adapted intermittently substantially simultaneously to move one of said color screens into and the other out of the path of predetermined rays from said burner, and means for independently adjusting the lengths of time during which said respective screens are positioned in the path of said rays.
9. In signal apparatus, in combination, a gas light, a device about said gas light comprising four color screens, two thereof being of like color and positioned substantially 180° apart and the other two of like color distinctive from said first color and positioned substantially 180° apart being positioned respectively between said first two screens, means for leading gas to said burner, and means actuated by the flow of said gas adapted intermittently to rotate said device through substantially 90° to interchange the positions of said respective screens with respect to said light.
10. In signal apparatus, in combination, a gas burner, a source of gas supply, a gas pressure chamber between said source and said burner, an inlet passage to said chamber leading from said source, an outlet passage from said chamber leading to said burner, a valve mechanism adapted in one position to open said inlet passage and close said outlet passage and in another position to close said inlet passage and open said outlet passage, a diaphragm exposed to gas pressure within said chamber and movable outwardly in response to flow of gas into said chamber from said source at opening of said inlet, spring means adapted to move said diaphragm inwardly upon flow of gas from said chamber to said burner at opening of said outlet, a connection between said valve mechanism and said diaphragm adapted to move said valve mechanism intermittently from one of its said positions to the other in conjunction with intermittent in and out movement of said diaphragm, a movable light screening member mounted adjacent said burner, and a connection between said diaphragm and said screen adapted upon predetermined movement of the former in one direction to substantially instantly move the latter into the path of predetermined rays from said burner and adapted upon predetermined movement of said diaphragm in the opposite direction to substantially instantly move said screen out of the path of said predetermined rays.
11. In a signal apparatus, in combination, a gas burner, a source of gas supply, a gas pressure chamber between said source and said burner, an inlet passage to said chamber leading from said source, an outlet passage from said chamber leading to said burner, a valve mechanism adapted in one position to open said inlet passage and close said outlet passage and in another position to close said inlet passage and open said outlet passage, a diaphragm exposed to gas pressure within said chamber and movable outwardly in response to flow of gas into said chamber from said source at opening of said inlet, spring means adapted to move said diaphragm inwardly upon flow of gas from said chamber to said burner at opening of said outlet, a connection between said valve mechanism and said diaphragm adapted to move said valve mechanism intermittently from one of its said positions to the other in conjunction with intermittent in and out movement of said diaphragm, and means actuated by the movements of said diaphragm adapted intermittently to change the color of light rays emitted in predetermined direction from said burner.
12. In signal apparatus, in combination, a gas burner, a source of gas supply, a gas pressure chamber between said source and said burner, an inlet passage to said chamber leading from said source, an outlet passage from said chamber leading to said burner, a valve mechanism adapted in one position to open said inlet passage and close said outlet passage and in another position to close said inlet passage and open said outlet passage, a diaphragm exposed to gas pressure within said chamber and movable outwardly in response to flow of gas into said chamber from said source at opening of said inlet, spring means adapted to move said diaphragm inwardly upon flow of gas from said chamber to said burner at opening of said outlet, a connection between said valve mechanism and said diaphragm adapted to move said valve mechanism intermittently from one of its said positions to the other in conjunction with intermittent in and out movement of said diaphragm, and means actuated by the movements of said diaphragm adapted intermittently to change the color of light rays emitted in predetermined direction from said burner.

let passage and in another position to close said inlet passage and open said outlet passage, a diaphragm exposed to gas pressure within said chamber and movable outwardly in response to flow of gas into said chamber from said source at opening of said inlet, spring means adapted to move said diaphragm inwardly upon flow of gas from said chamber to said burner at opening of said outlet, a connection between said valve mechanism and said diaphragm adapted to move said valve mechanism intermittently from one of its said positions to the other in conjunction with intermittent in and out movement of said diaphragm, means about said burner comprising a member adapted to permit passage of light rays of a predetermined color and a second member angularly disposed relative to said first member adapted to permit passage of light rays of a second predetermined color, and means actuated by the in and out movements of said diaphragm adapted to move said last means to intermittently interchange the positions of said two members with respect to said burner.

13. In a signal apparatus, in combination, a gas burner, a source of gas supply, a gas pressure chamber between said source and said burner, an inlet passage to said chamber leading from said source, an outlet passage from said chamber leading to said burner, a valve mechanism adapted in one position to open said inlet passage and close said outlet passage and in another position to close said inlet passage and open said outlet passage, a diaphragm exposed to gas pressure within said chamber and movable outwardly in response to flow of gas into said chamber from said source at opening of said inlet, spring means adapted to move said diaphragm inwardly upon flow of gas from said chamber to said burner at opening of said outlet, a connection between said valve mechanism and said diaphragm adapted to move said valve mechanism intermittently from one of its said positions to the other in conjunction with intermittent in and out movement of said diaphragm, a device rotatably mounted about said burner comprising four color screens, two thereof being of like color and positioned substantially 180° apart and the other two being of like color and distinctive from said first color and positioned substantially 180° apart, being positioned respectively between said first two screens, and means actuated by the in and out movements of said diaphragm adapted to oscillate said device through substantially 90° to interchange the positions of said respective colored screens with respect to said burner.

14. In signal apparatus, in combination, a gas burner, a source of gas supply, a gas pressure chamber between said source and said burner, an inlet passage to said chamber

leading from said source, an outlet passage from said chamber leading to said burner, a valve mechanism adapted in one position to open said inlet passage and close said outlet passage and in another position to close said inlet passage and open said outlet passage, a diaphragm exposed to gas pressure within said chamber and movable outwardly in response to flow of gas into said chamber from said source at opening of said inlet, spring means adapted to move said diaphragm inwardly upon flow of gas from said chamber to said burner at opening of said outlet, a connection between said valve mechanism and said diaphragm adapted to move said valve mechanism intermittently from one of its said positions to the other in conjunction with intermittent in and out movement of said diaphragm, a device rotatably mounted about said burner comprising four color screens, two thereof being of like color and positioned substantially 180° apart and the other two being of like color and distinctive from said first color and positioned substantially 180° apart, being positioned respectively between said first two screens, and means actuated by the in and out movements of said diaphragm adapted to oscillate said device through substantially 90° to interchange the positions of said respective colored screens with respect to said burner.

15. In signal apparatus in combination, a gas burner, a source of gas supply, a gas pressure chamber between said source and said burner, an inlet passage to said chamber leading from said source, an outlet passage from said chamber leading to said burner, a valve mechanism adapted in one position to open said inlet passage and close said outlet passage and in another position to close said inlet passage and open said outlet passage, a diaphragm exposed to gas pressure within said chamber and movable outwardly in response to flow of gas into said chamber from said source at opening of said inlet, spring means adapted to move said diaphragm inwardly upon flow of gas from said chamber to said burner at opening of said outlet, a connection between said valve mechanism and said diaphragm adapted to move said valve mechanism intermittently from one of its said positions to the other in conjunction with intermittent in and out movement of said diaphragm, means adjacent said burner comprising a member adapted to give light rays therefrom of predetermined color and a member adapted to give said light rays a second predetermined color, and a connection between said coloring means and said diaphragm adapted upon predetermined movement of said diaphragm in one direction to substantially instantly render one of said coloring means effective upon predeter-

mined light rays from said burner and adapted upon predetermined movement of said diaphragm in the other direction to substantially instantly render said other coloring member effective upon said predetermined rays.

16. In signal apparatus, in combination, a gas burner, a source of gas supply, a gas pressure chamber between said source and said burner, an inlet passage to said chamber leading from said source, an outlet passage from said chamber leading to said burner, a valve mechanism adapted in one position to open said inlet passage and close 10 said outlet passage and in another position to close said inlet passage and open said outlet passage, a diaphragm exposed to gas pressure within said chamber and movable outwardly in response to flow of gas into 15 said chamber from said source at opening of said inlet, spring means adapted to move said diaphragm inwardly upon flow of gas from said chamber to said burner at opening of said outlet, a connection between said 20 valve mechanism and said diaphragm adapted to move said valve mechanism intermittently from one of its said positions to the other in conjunction with intermittent in and out movement of said diaphragm, 25 means actuated by the movements of said diaphragm adapted intermittently to change the color of light rays emitted in predetermined direction from said burner, and means exterior of said chamber for leading 30 gas from said source to said burner to continually supply said burner irrespective of the opening and closing of said valves.

17. In signal apparatus, in combination, a gas burner, a source of gas supply, a gas pressure chamber between said source and said burner, an inlet passage to said chamber leading from said source, an outlet passage from said chamber leading to said burner, a valve mechanism adapted in one 40 position to open said inlet passage and close said outlet passage and in another position to close said inlet passage and open said outlet passage, a diaphragm exposed to gas pressure within said chamber and movable 45 outwardly in response to flow of gas into said chamber from said source at opening of said inlet, spring means adapted to move said diaphragm inwardly upon flow of gas from said chamber to said burner at opening 50 of said outlet, a connection between said valve mechanism and said diaphragm adapted to move said valve mechanism intermittently from one of its said positions to the other in conjunction with intermittent in and 55 out movement of said diaphragm, means actuated by the movements of said diaphragm adapted intermittently to change the color of light rays emitted in predetermined direction from said burner, and means for in-

dependently adjusting the rate of movement of said diaphragm in each direction. 65

18. In signal apparatus, in combination, a gas burner, a source of gas supply, a passage for gas from said supply to said burner, a diaphragm exposed to gas pressure in 70 said passage, means actuated by the flow of said gas adapted to give said diaphragm a back and forth movement, a movable light screening member adjacent said burner, and a connection between said screening member and said diaphragm adapted upon predetermined movement of said diaphragm in one direction to substantially instantly move said screening member into the path of predetermined rays from said burner and adapted upon predetermined movement of 75 said diaphragm in the opposite direction to substantially instantly move said screening member out of the path of said predetermined rays. 80

19. In signal apparatus, in combination, a gas burner, a source of gas supply, a passage for gas from said supply to said burner, a diaphragm exposed to gas pressure in said passage, means actuated by the flow of said gas adapted to give said diaphragm a back and forth movement, a movable light screening member adjacent said burner, a connection between said screening member and said diaphragm adapted upon predetermined movement of said diaphragm in one direction to substantially instantly move said screening member into the path of predetermined rays from said burner and adapted upon predetermined movement of 90 said diaphragm in the opposite direction to substantially instantly move said screening member out of the path of said predetermined rays, and means for independently adjusting the rate of movement of said diaphragm in each direction. 95

20. In signal apparatus, in combination, a gas burner, a source of gas supply, a passage for gas from said supply to said burner, a diaphragm exposed to gas pressure in said passage, means actuated by the flow of said gas adapted to give said diaphragm a vibratory movement, a device rotatably mounted about said burner comprising a plurality of color screens, and means actuated by the vibrations of said diaphragm adapted at predetermined intervals of time and substantially instantly to rotate said device through a predetermined angle. 105

21. In signal apparatus, in combination, a gas burner, a source of gas supply, a passage for gas from said supply to said burner, a diaphragm exposed to gas pressure in said passage, means actuated by the flow of said gas adapted to give said diaphragm a vibratory movement, a device rotatably mounted about said burner comprising four color screens, two thereof being of 110

like color and positioned substantially 180° apart and the other two being of like color and distinctive form said first color and positioned substantially 180° apart, being 5 respectively positioned between said first two screens, and means actuated by the vibrations of said diaphragm adapted intermittently to rotate said device through substantially 90° to interchange the positions of 10 said respective colored screens with respect to said burner.

22. In signal apparatus, in combination, a standard adapted to be positioned at a highway intersection, a gas burner upon said 15 standard, a casing upon said standard about said burner having means adapted to permit passage of light rays from said burner along each of said highways, a source of gas supply within said standard, means for 20 leading gas from said source to said burner, a rotatable device within said casing about said burner comprising a plurality of color screens adapted distinctively to color the light rays directed from said burner along 25 each of said respective highways in both directions, and means actuated by the flow of gas to said burner adapted at predetermined intervals of time to rotate said device to change the coloring of the light rays 30 directed along each of said respective highways in both directions.

23. In signal apparatus, in combination, a standard adapted to be positioned at the intersection of two highways, a gas burner 35 upon said standard, a casing upon said standard about said burner having means adapted to permit passage of light rays from said burner along each of said highways, a source of gas supply within said standard, 40 means for leading gas from said source to said burner, a rotatable device within said casing about said burner comprising four screens adapted to distinctively color the light rays directed from said burner along 45 each of said respective highways in both directions, and means actuated by the flow

of gas to said burner adapted at predetermined intervals of time to rotate said device through substantially 90° to interchange the coloring of the light rays directed 50 along each of said highways in both directions.

24. In signal apparatus, in combination, a standard adapted to be positioned at a highway intersection, a gas burner upon 55 said standard, a casing upon said standard about said burner having means adapted to permit passage of light rays from said burner along each of said highways, a source of gas supply within said standard, means for 60 leading gas from said source to said burner, a rotatable device about said burner comprising four color screens, two thereof being of like color and positioned substantially 65 180° apart and the other two of like color distinctive from said first color and positioned substantially 180° apart being positioned respectively between said first two screens, and means actuated by the flow of said gas to said burner adapted at predetermined intervals of time to rotate said device through substantially 90° to interchange the positions of said respective screens with respect to said light.

25. In signal apparatus, in combination, a 75 gas burner, a source of gas supply, a passage for gas from said supply to said burner, a pressure chamber in said passage, a diaphragm in said chamber, a valve mechanism actuated by said diaphragm adapted 80 to cause intermittent flow of gas through said chamber to said burner, means actuated by the movements of said diaphragm adapted intermittently to change the color of light rays emitted from said burner, and a passage for gas from said source to said burner exterior of said chamber to provide for a continuous supply of gas to said burner.

In testimony whereof, I have signed my name to this specification this 6th day of 90 February 1924.

ARTHUR P. HAGAR.
